BRUSH AND ASSOCIATED DISPENSING
MEANS FOR POWDER MATERIAL

Lydia Mead, Moravia, N. Y.

Application August 16, 1940, Serial No. 352,848

1 Claim. (Cl. 15—138)

My invention relates to a brush having means associated therewith by which powder material may readily be dispensed or scattered upon a surface to be cleaned.

My invention has further reference to an associated brush and chamber for the powder material, the chamber being provided with a dispensing opening which, normally, is sealed so that water does not enter said chamber even though the brush be entirely submerged in water.

My invention has further reference to a combined arrangement of the character stated wherein the chamber is provided with a normally sealed dispensing opening and, in addition, with a filling opening normally sealed by a closure cap which may readily be detached when it becomes desirable to replenish the supply of the powder material in the aforesaid chamber.

Various other objects, advantages and features of my invention will become apparent from the following detailed description.

My invention resides in the brush arrangement, sealed dispensing means, features and combinations of the character hereafter described and claimed.

For an understanding of my invention and for an illustration of some of the forms thereof, reference is to be had to the accompanying drawings, in which:

Figure 1 is a perspective view showing a brush and associated dispensing means as constructed in accordance with the invention;

Fig. 2 is a vertical sectional view, partly in elevation, showing the brush of Fig. 1;

Fig. 3 is a vertical sectional view, partly in elevation, showing a modification of the invention;

Fig. 4 is a transverse, vertical sectional view, partly in elevation, taken on the line 4—4 of Fig. 4 looking in the direction of the arrows;

Fig. 5 is a horizontal sectional view taken on the line 5—5 of Fig. 3 looking in the direction of the arrows;

Fig. 6 is a transverse vertical sectional view, partly in elevation, showing a modification of the invention; and

Fig. 7 is an elevational view, partly in section, showing a modification of the invention.

It is common practice, when cleaning or scrubbing a floor or other surface with a brush, for a can of cleaning or scrubbing powder to be at hand. After the brush has been used for some time, it is laid down, the can of powder picked up and some of the powder sprinkled on

the surface to be cleaned. Thereupon, the can of powder is set down, the brush picked up and the brushing continued, these operations being alternately proceeded with as long as may be necessary. By my invention, there is provided a combined brush and powder holder which greatly simplifies and speeds up the ordinary brushing or scrubbing operation.

For an illustration of my novel device, reference is to be had to Figs. 1 and 2 wherein there is shown a handle or back H formed from a relatively thick base 1 and a relatively thinner wall 2, the base 1 and wall 2 being spaced apart so as to form a chamber 3. Preferably, although not necessarily, the base 1 and wall 2 are molded or otherwise suitably formed from an artificial resin, a phenol condensation product or the like. The chamber 3 is adapted to contain a quantity of a cleaning or scrubbing powder or pulverized material, such as that known as Old Dutch Cleanser, or the like. Hereinafter, powder or material of this character is generically referred to as "cleaning powder."

As clearly indicated on the drawing, the handle H is of minimum width in the central area thereof, the width increasing to some extent toward each end of said handle H. Furthermore, the wall 2 in the area thereof at one end of the brush, comprises, preferably, a relatively plane, flat section, said wall 2, in the area thereof toward the other end of the brush, preferably, sloping upwardly to thereby increase the depth of the chamber 3. The outer surfaces of the base 1 and wall 2 should be of smooth, curved configuration, as illustrated. With an arrangement of this character, the person using the brush may conveniently grasp the same by applying the palm of the hand to the aforesaid plane, flat section of the wall 2, the thumb and fingers being applied to the respective opposite sides of the handle H.

In accordance with one form of the invention, a filling opening together with a closure cap arrangement therefor is provided for the chamber 3 and, preferably, this filling opening is formed in the above noted plane, flat section of the wall 2. Thus, as shown in Fig. 2, said wall 2 comprises a circular filling opening 4 defined by a thickened section 2a of said wall 2, this thickened section 2a having a plurality of inwardly projecting members 2b disposed thereon in symmetrical spaced relation, and said thickened section 2a comprising a flanged seat 2c formed above said members 2b.

Coactable with the filling opening 4 is a closure

cap 5 which comprises a circular plug section 5a, a flanged section 5b and a handle member 5c. Projecting outwardly from the plug section 5a are a plurality of members 5d disposed thereon in symmetrical spaced relation.

As will be understood from the drawing, movement of the closure cap axially of the filling opening 4 to closing position causes the spaces between the members 2b of the filling opening to snugly receive the members 5d of the closure cap, and the spaces between the members 5d of the closure cap to snugly receive the members 2b of the filling opening. With the closure cap in seated position, the members 5d of the closure cap are just below the members 2b of the filling opening. The upper surfaces of the closure cap members 5d are suitably inclined and the same is true of the lower surfaces of the filling opening members 2b. Accordingly, with the closure cap seated in the filling opening, rotation of the same through a small angle causes the coating sets of members 2b and 5d to exercise a cam effect whereby the closure cap is forced downwardly to thereby compress a rubber gasket 6, which previously has been seated on the flanged section 5b of the closure cap, against the flanged seat 2c of the filling opening.

In view of the foregoing, it will be understood that, with the described closure cap arrangement, the filling opening 2 may be sealed effectively against the passage or seepage of liquid therethrough. In lieu of the described arrangement, it will be understood that other equivalent closure cap arrangements may be utilized.

Further in accordance with the invention, a dispensing opening is provided for the chamber 3 and, preferably, this dispensing opening is formed adjacent the end of the handle H removed from the filling opening 2. Thus, as shown in Figs. 1, 2 and 3, the wall 2 comprises a circular dispensing opening 7 adapted to be sealed against the passage of liquid by a semi-spherical plug 8 formed from rubber, or equivalent. The member 8 is carried by one end of a lever 9 pivoted at 10 upon a pair of spaced members 11 upstanding from the wall 2. The lever 9 should be positively biased in a counter-clockwise direction, Fig. 2, and, to this end, there may be utilized a spring 12 which is wound around a pin 13 supported by opposite sides of said lever 9, one end of the spring engaging the upper surface of the wall 2 and the other end thereof engaging the lower surface of the finger piece 9a.

As the lever 9 is shown in Figs. 1, 2 and 3, it will be understood that the spring 12 cooperates with the lever 9 to effectively hold the plug 8 seated in the opening 7. By pressure applied to the finger piece 9a, the lever 9 may readily be swung to a position causing the dispensing opening 7 to be opened. It will be understood that equivalent arrangements other than the one shown may be utilized for sealing the dispensing opening 7.

Secured in suitable manner to the lower surface of the base 1 of the handle H are the tufts or bunches of bristles B which may be of the usual character used in brushes of the character described. These may be secured to the base 1 during the molding operation or otherwise as may be desirable.

In operation, the closure cap 5 is removed and a desired quantity of cleaning powder passed into the chamber 3 through the filling opening 4.

Thereupon, the closure cap 5 is returned to and locked in its sealing position. The brush is now in condition for use. With the lever 9 held in closed position by the spring 12, the entire brush 5 may be dipped into a pail or other receptacle containing water. When this is done, by reason of the seals existing, respectively, at the filling opening 4 and the dispensing opening 7, there is no leakage of water into the chamber 3 even though the brush is moved entirely under water. As use of the brush continues, the operator, from time to time, may depress the finger piece 9a, this being conveniently located near the operator's index finger, and, after partially or entirely inverting the brush, sprinkle such amount of the cleaning powder material as may be desired upon the surface being cleaned. As often as desirable, the brush may be dipped into the supply of water, and, each time that this is done, it will be understood that the plug 8 should be in sealing position as regards the dispensing opening 7. From the foregoing description, it will be understood that the chamber 3 may readily be filled with cleaning powder as often as required and that such powder may conveniently be dispensed as the cleaning operation proceeds.

Referring to Figs. 3, 4 and 5, I have illustrated a form of the invention wherein the brush comprises a plate or member 15 which, for example, may be formed from wood or equivalent, the tufts of bristles B being held in the plate 15 in a manner known in the art. Adapted to be associated with the plate 15 is a chamber or receptacle 16 for the cleaning powder, this chamber 16 being provided with a dispensing arrangement, and with a filling arrangement if desired, of the general character hereinbefore described in connection with Figs. 1 and 2.

In accordance with the novel feature of the form of the invention shown in Figs. 3, 4 and 5, the bottom wall 17 of the chamber 16 may be provided with a dovetail groove 17a, the top surface of the plate 15 being provided with a dovetail rib 15a adapted to interlock with the groove 17a. As shown in Fig. 5, the dovetail rib 15a may taper from end-to-end thereof and the dovetail groove 17a may be of similar tapered configuration. With such an arrangement, as will be understood, the chamber wall 17 may be associated with the plate 15 by effecting relative endwise movement of said wall and plate after the rib 15a has been alined axially with the groove 17a, the rib 15a engaging the groove 17a so as to securely unite the parts together. It will be understood that the taper of the rib 15a and the groove 17a should be such that the rib comes into binding relation on the walls of the groove at the time that the chamber 16 is properly positioned on the plate 15.

In Fig. 6, I have shown a modified arrangement which comprises a bottom bristle-supporting plate 18 formed from wood or equivalent, the top surface of this plate 18, in conjunction with a chamber-forming wall 19 secured thereto in suitable manner, defining the chamber in which the cleaning powder is disposed. The plate 18 comprises a dispensing opening or passage 18a adapted to be closed by a tapered plug 20 of rubber or the like, this plug 20 being carried by a stem 21 which extends vertically through the powder-containing chamber and terminates in an upper knob 22 slideable in an opening extending through the member 19 in vertical alinement with the dispensing opening 18a. The plug 20 together with its stem 21 and knob 22 should be

suitably biased in an upward direction, as by a spiral spring 23 encircling the stem 21, the lower section of said spring 23 engaging the top surface of the plate 18 and the upper section of the spring 23 engaging a member 24 formed from rubber or the like, the outer edge of this member 24 being anchored in an interior flange 19a of the member 19 and the inner surface of said member 24 engaging and being secured to the lower surface of the knob 22 so as to seal the passage or opening in which the knob 22 is slideable.

It will be understood that the knob 22 should be positioned on the brush structure in somewhat the same relation as is the finger piece 9a in the form of the invention hereinbefore described. Obviously, when it becomes desirable to dispense a quantity of the cleaning powder from the powder chamber, it is necessary merely to depress the knob 22 by finger action while holding the brush more or less in its normal scrubbing position. With the knob 22 thus depressed, the dispensing opening 18a is open for the downward passage therethrough of the cleaning powder which comes to rest upon the floor or other surface being cleaned. With an arrangement of the character described in Fig. 6, it will probably be desirable for the plate 18 to be free from tufts of the bristles B in the immediate vicinity of the dispensing passage 18a.

Although my invention has been hereinbefore described in connection with a chamber or receptacle for the cleaning powder which is to have a filling opening adapted to be sealed by a detachable closure cap, it shall be understood that the invention is not to be thus limited. For example, as shown generally in Figs. 3, 4 and 5, a suitable arrangement may be provided for detachably retaining the powder-containing chamber to the bristle-supporting plate of the brush. With such an arrangement, when the powder-supporting chamber becomes empty, the same may be readily removed from the bristle-supporting plate and a new filled powder-containing chamber associated with said plate. Obviously, with such an arrangement, the provision of a filling opening and a detachable closure cap therefor is neither necessary nor required.

Referring to the form of my invention shown in Fig. 7, there is illustrated a modified handle or back H¹ having a lower groove or channel 15b formed therein, this groove or channel, pref-

erably, extending entirely around the lower surface of said handle or back H¹. In lieu of the tufts of bristles, there is associated, preferably in detachable relation, with the channel 15b, a scrubbing or polishing structure S such, for example, as artificial sponge, the structure S being preformed to provide an upstanding flanged section s adapted to resiliently embrace the surfaces forming the channel 15b. Obviously, the structure S may be attached to the handle H¹ otherwise than in the resilient manner noted above.

Aside from the foregoing, the handle H¹ is of substantially the same character as the handle H previously described.

While the invention has been described with respect to certain particular preferred examples which give satisfactory results, it will be understood by those skilled in the art after understanding the invention, that various changes and modifications may be made without departing from the spirit and scope of the invention and it is intended therefore in the appended claim to cover all such changes and modifications.

What is claimed as new and desired to be secured by Letters Patent is:

In a brush of the character described, a base, a scrubbing or polishing structure secured to the lower side of said base and extending substantially throughout the length thereof, a wall formed integrally with said base at the side thereof opposite said structure, said wall being coextensive in length with said base and forming therewith a chamber for cleaning powder or the like, said integral wall having a powder-dispensing opening formed therein, means for sealing said dispensing opening to prevent the passage of water into said chamber when the brush is submerged, a pivoted lever to which said sealing means is secured, means for biasing said lever to a position wherein it holds said sealing means in sealing position with respect to said dispensing opening, said opening, said sealing means, said lever and said biasing means being located between one end of said brush and the middle thereof, said integral base serving as a handle for the brush and being adapted to be gripped by the hand of the user in such manner that the palm of the hand rests upon said integral base in the area thereof removed from said lever and with one finger of the hand conveniently located to operate said lever.

LYDIA MEAD.
